UNITED STATES PATENT OFFICE.

LAWRENCE MAPLES, OF TOLEDO, OHIO.

WASHING MACHINE.

Application filed June 19, 1922. Serial No. 569,312.

To all whom it may concern:

Be it known that I, LAWRENCE MAPLES, a subject of the Kingdom of Great Britain, and a resident of Toledo, Lucas County, and 5 State of Ohio, have invented certain new and useful Improvements in Washing Machines, of which the following is declared to be a full, clear, and exact description.

This invention relates to washing machines and more particularly to supports for the agitating mechanism of washing machines, and its principal object is to provide a support for washing machine mechanism, constructed and arranged to convert an ordinary wash tub into a washing machine. Another object is to provide a support for washing machine mechanism of this class, which shall be rugged and of substantial construction, although light in weight, and 10 one which shall be simple and highly efficient for the purpose intended. Another object is to provide a novel, rigid support for the agitating mechanism, with extensible supporting arms, which may be adjusted to accommodate the support to tubs of large or small diameter within a given range. Another object is to provide novel means for supporting the dolly in operative and inoperative positions. Other objects and advantages will 15 appear in the course of this specification, and with said objects and advantages in view this invention consists in several novel features hereinafter set forth and claimed.

The invention is clearly illustrated in the 20 accompanying drawings in which:

Fig. 1. is a side elevation of washing machine mechanism embodying a simple form of the present invention, and showing the same applied to a wash tub, the latter being 25 shown in vertical cross section; Fig. 2. is a plan of the machine; Fig. 3 is a detail, vertical cross section taken on line 3—3 of Fig. 1; Fig. 4. is a detail, vertical cross section taken on line 4—4 of Fig. 2; Fig. 5. is a detail, fragmental view of the dolly and its support, partly in vertical section and partly in side elevation, the line of section being indicated at line 5—5 in Fig. 2, and the dolly being shown in its operative position clutched 30 to the dolly shaft; Fig. 6, is a detail, fragmental, vertical section of the dolly shaft and dolly, and showing the dolly in its raised or inoperative position; Fig. 7, is a detail, horizontal section taken on the line 7—7 of Fig. 5; Fig. 8, is a detail, horizontal section, taken 55 on line 8—8 of Fig. 5; and Fig. 9, is a detail, horizontal section taken on line 9—9 of Fig. 6.

Referring to said drawings, the reference number A designates a fragment of an ordinary wash tub, which may be constructed of 60 metal or wood as is well understood. Supported upon the wash tub A, is a washing machine mechanism, embodying one form of the present invention. The support for the 65 agitating mechanism of the machine comprises a centrally located, disc like plate, 6, which is formed with arms 7 that radiate therefrom. The support may be cast, or it may be formed of pressed metal work or of any desired material. The plate 6 and its 70 arms 7 are preferably in the form of a single piece of material, having a comparatively thin horizontal web portion 8, the edges of which are curved downwardly to provide 75 stiffening flanges 9, 10, the flanges 9 being at the margin of the central disc like portion, and the flanges 10 being at the sides of the arms 7. The flanges of each arm run parallel 80 with each other and serve also as guide members for the auxiliary or extensible arms 11. On the under sides of the arms 7, are the extensible arms 11; they are formed of comparatively thin web portions 12, and their side edges are curved downwardly to form 85 strengthening flanges 13, that are guided between the downturned flanges 10 of the arms 7. The extensible arms 11 are secured to the arms 7 by bolts 14 and wing nuts 15, the bolts extending through bolt holes in the extensible arms, and through radial slots 16 90 formed in the horizontal web portions 8 of the arms 7. The nuts are threaded upon the bolts and bear against the upper faces of the web portions 8 of the arms 7. The extensible arms are adjustable lengthwise of 95 the arms 7 to accommodate the support to tubs of different diameter, and if desired said extensible arms may be formed with additional bolt holes 17 to provide for a greater range of adjustment, the bolts 14 being capable of extending through the outer or inner bolt holes of the extensible arms. The outer ends of the extensible arms 11 are formed with downwardly projecting lugs 18 100 in which are threadedly mounted thumb screws 19, which may be screwed up against

the outer sides of the tub upon which the support is to be attached.

The agitating members of the washing machine may take various forms, and in the 5 simple form, illustrated, the agitating mechanism comprises a vertical dolly shaft 20, which is journalled in bearing bosses 21 formed on the central disc like plate 6, a dolly or dasher 22 of conventional form 10 carried by the lower end of the dolly shaft 20, a beveled pinion 23 secured upon the upper end of the dolly shaft 20, and a beveled gear segment 24 rotatively mounted upon a stud shaft 25, secured in a bracket 15 26 which is mounted upon the central disc like plate and is bolted or otherwise fastened thereto. The bracket 26 has a cross bar 27 formed on it, in which is formed a bearing aperture for the extreme upper end of the 20 dolly shaft 20. The gear segment 24 is held on said shaft by a cotter pin 28 and is formed with a handle socket 29, in which is secured a handle 30, by means of which the gear segment is rocked back and forth 25 in operating the agitating mechanism.

For the purpose of condensing the size of the machine for shipment and storage, and as to the matter of convenience in handling the machine, the dolly or dasher 30 22 is capable of being supported in an operative position, as illustrated in Fig. 5, in which position the dolly is clutched to the dolly shaft and rotates therewith, and in an inoperative position, in which it is raised 35 upon the dolly shaft and is suspended thereby, in a position closer to the support 6 as is seen in Figs. 1 and 6. The simple means for supporting the dolly in the two positions comprises a sleeve 30 secured upon 40 the dolly shaft 20 and having a head or enlargement 31 upon its lower end, and a plurality of ribs 32 that extend up from said head 31. The dolly 22 has a coupling or clutch member 33, secured to its upper 45 side by bolts 34, and said coupling member 33 has a central aperture 35 and notches 36 through which the sleeve 30 and webs 32 extend, thereby providing clutch mechanism between the dolly and dolly shaft. Projecting 50 down from the coupling member 33 are clutch jaws 37 that also engage with the ribs 32, and when the dolly is in its operative position said jaws 37 rests upon the enlargement 31 of the sleeve 30. Secured 55 upon the bottom face of the dolly 22 by the bolts 34, is a cup like member 38 which receives the lower end of the sleeve 30, and protects the clothes against any injury from the dolly shaft or its sleeve.

60 It is obvious that the dolly is capable of up and down movement, on the dolly shaft, without being uncoupled therefrom, so long as the coupling member 33 and jaws 37 remain in clutching engagement with the webs 65 32. To secure the dolly in raised or inopera-

tive position, the dolly is lifted until the jaws 37 are disengaged from the webs 32, and then turned part way around, so that the clutch jaws 37 rest upon the webs 32, as is clearly seen in Fig. 6.

70 It will be observed from the above that a very light weight support is provided, which, however, is extremely rugged, and substantial, and is capable of supporting the agitating mechanism in place upon an ordinary wash tub. It can be readily adjusted to accommodate itself to tubs of various sizes. By continuing the down turned flanges of the central disc like portion, along the sides of the radiating arms, the entire 75 support is thereby strengthened and reinforced, and at the same time, guides are provided, between which the extensible arms are slidably held and maintained in position, irrespective of their position of adjustment under the arms.

80 85 More or less variation of the exact details of construction is possible without departing from the spirit of this invention; I desire, therefore, not to limit myself to the exact form of the construction shown and described, but intend, in the following claims, to point out all of the invention disclosed herein.

90 I claim as new and desire to secure by Letters Patent:

95 1. An improved support for an agitating device for converting a tub into a washing machine, comprising a central disc like frame member formed with a plurality of 100 arms, radiating, therefrom, the marginal edges of the frame member, and side edges of the arms being formed with downwardly turned strengthening flanges continuous along said edges, and arm extensions on the 105 under sides of the arms, having upper faces conforming to the lower faces of the arms and guided thereby, and means for adjustably securing said arm extensions to the 110 arms of the frame member.

115 2. An improved support for an agitating device for converting a tub into a washing machine, comprising a supporting frame formed with a central disc like frame member having a plurality of arms radiating therefrom, the marginal portions of the central disc like member and sides of the arms having down turned continuous strengthening flanges, arm extensions on the under side of said arms and guided to move radially between said flanges, means for adjustably securing said arms and arm extensions together, and tub engaging screws 120 threadedly secured in the outer ends of said arm extensions.

125 3. An improved support for an agitating device for converting a tub into a washing machine, comprising a central disc like member and arms radiating therefrom, the marginal edge of the disc like mem- 130

- ber and side edges of the arms being down turned to provide strengthening flanges continuous along said edges, and tub engaging arm extensions having down turned flanges 5 on their side edges guided between the flanges of the arms, said arm extensions being adjustably secured to said arms.
4. In a washing machine, a support, a dolly shaft journalled therein and having a 10 head on its lower end and a plurality of upright ribs extending up from said head, a dolly, and a coupling member secured to said dolly and being apertured and notched to receive said shaft and ribs, said coupling 15 member resting on said head and being capable of being lifted above said ribs whereby it may be partially turned with respect to the dolly shaft to bring the notches out of register with the ribs whereby it may be supported thereon.
5. In a washing machine, a support, a dolly shaft journalled therein, a sleeve secured on said dolly shaft and formed with a head on its lower end and a plurality of 20 ribs extending up from the head, a dolly, and a coupling member secured thereto and having a central aperture and notches for receiving said sleeve and its ribs, and having also downwardly extending clutch jaws 25 adapted in one position of the dolly, to rest upon the head of the sleeve, and adapted, 30 upon the head of the sleeve, and adapted,
- in another position of the dolly, to rest upon said ribs.
6. In a washing machine, a support, a dolly shaft journalled therein, a sleeve secured to said dolly shaft and formed with a head on its lower end and a plurality of ribs extending up from the head, a dolly, a coupling member secured thereto and having a central aperture and notches for receiving said sleeve and its ribs and having also downwardly extending clutch jaws 35 adapted, in one position of the dolly, to rest upon the head of the sleeve, and adapted, in another position of the dolly, to rest upon 40 said ribs, and a cup like member secured to the bottom of the dolly in axial alignment with the dolly shaft and adapted to receive the lower end of the sleeve in one position of the dolly on the dolly shaft. 45
7. In a washing machine the combination of a support having a central horizontal, flat, web portion and supporting arms radiating therefrom, and clamping means for clamping said support upon a tub, said 50 central web portion and arms being formed on their edges with down turned strengthening flanges continuous along said edges, and agitating mechanism supported by the said central web like portion.

LAWRENCE MAPLES.
